UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

AUTOMATICALLY-THREADING SHUTTLE FOR LOOMS.

Application filed October 14, 1926. Serial No. 141,520.

This invention relates to automatically threading shuttles for looms wherein the shuttle becomes threaded after replenishment of filling or after an overthrow without removal of the shuttle from the loom and is in part a continuation of and substitution for a prior application, Serial No. 79,990, filed January 8, 1926, which has been abandoned,

Automatically threading shuttles, as heretofore constructed, have usually been provided with a threading block having an apron, usually overhanging the side delivery eye and terminating at its forward end in a thread director for directing the thread to the side delivery eye during complete threading of the shuttle. During weaving, the shuttle is subject to the main binder pressure, as it enters the shuttle box, at the breast portion of the shuttle; that is, at a point laterally opposite the threading block and substantially near the rear end portion of the block, and it has heretofore been the practice to maintain as much strength as possible at the breast of the shuttle to prevent cracking or breaking the shuttle wood.

The effect of these two conditions has resulted in the formation of obstructions or shoulders, either in the shuttle body or the apron of the threading block where these two parts come together. In weaving with a narrow open shed, the warp threads in the upper plane of the shed, frequently ride over in contact with the front wall of the shuttle, with the result that the shoulders or projections formed at the union of the shuttle body and the apron of the threading block frequently break the warp threads in the upper plane of the shed and necessitate stopping the loom. This is particularly observable in the use of the automatically threading shuttle in looms with narrow open shed, because, as the shuttle enters the shed, the threads in the upper plane of the shed are encountered first by the end portion of the shuttle slightly back of the tip thereof, and such threads then ride along the surface of the front wall of the shuttle and upon encountering projections or shoulders or other obstructions between the shuttle body and the apron of the block, such threads catch and become broken.

The object of the present invention, therefore, is to provide an automatically threading shuttle having its front wall, which is adjacent the fell of the cloth during weav-

ing, cut away in a frontward and forward uniformly curved surface from a point back of the shuttle breast to a point forward of the side delivery eye, and associating therewith a threading block wherein the apron is provided with a similar frontwardly and forwardly extending surface corresponding to the plane of the curved surface of the front wall of the shuttle body, thereby doing away with all projections or obstructions that would be liable to break the warp threads in the upper plane of the shed.

In accordance with the present invention, the front wall of the shuttle body is rounded and uniformly curved in a frontwardly, downwardly and forwardly direction towards the end of the shuttle and the apron of the threading block is similarly curved frontward, downward, and forward in the same plane as the curve formed in the shuttle body, so that the surfaces presented to the warp threads in the upper plane of the shed merge into each other without offering obstructions or sudden lifting projections to the overriding warp threads, and in order to support the wood of the shuttle at the shuttle breast, the threading block is formed of a non-yielding material, such as cast iron or the like. The result of this combination is that the non-yielding threading block at the inside portion of the shuttle adjacent the shuttle breast lends an effective support to the shuttle at this point where the greatest crushing strain is exerted upon the shuttle as it is arrested in the shuttle box.

The invention will best be made clear from the following description and the accompanying drawings of one good practical form thereof.

In the drawings:

Fig. 1 is a side elevation of an automatically threading shuttle provided with the present invention;

Fig. 2 is an enlarged perspective view of such a shuttle showing the merging of the uniformly curved surfaces of the shuttle wood and surface of the apron;

Fig. 3 is a sectional elevation through the lay, with parts broken away, showing a narrow open shed with a shuttle of the present invention employed in connection therewith;

Fig. 4 is a diagrammatic view, showing the threads in the upper plane of the shed bearing upon the front wall of the shuttle as it passes through the shed; and

Fig. 5 is a plan view of the threading end

of a shuttle containing the present invention.

The shuttle body 1 is formed of wood, as usual, and is provided with the usual bobbin chamber 2, the bottom of which is open for the ejection of a spent filling carrier during replenishment of filling. Forward of the bobbin chamber 2 the shuttle is provided with a threading block receiving chamber 3 in which is supported the threading block 4 which, as shown, is of the thread casting type, similar in this respect to the shuttle shown and described in the patent to Edward S. Stimpson, No. 1,309,226, July 8, 1919. The threading block 4 has the longitudinally extending thread passage and the thread casting scroll 5, which, on the formation of a loop or overthrow as the shuttle is brought to rest in the replenishing box, casts the thread upwardly out of the longitudinally extending thread passage. During weaving, the thread passes through the scroll 5, over the bridge 6, and then is turned laterally through the side delivery eye 7. The front wall 8 of the shuttle 1 which is adjacent the fell of the cloth during weaving, is cut away from the point 9 which is back of the shuttle breast 10, and such cut away portion of the shuttle wood extends frontwardly, as at 11, (indicated in Figs. 1 and 2) and downwardly and forwardly, in a uniform curve to the end portion 12 of the shuttle. The curved portion formed in the wall of the shuttle body is uniform from end to end and from top to bottom, with the result that a smooth, gradual, warp-lifting and sliding surface is presented to the warps in the upper plane of the shed during weaving.

The threading block 4 is provided with an apron 13 overhanging the side delivery eye 7, and the exterior surface of the apron 13 has likewise a frontwardly, downwardly and forwardly extending surface 14 in the plane of the surface formed in the front wall of the shuttle wood, the result being that as the warp threads *a* (as indicated in Figs. 3 and 4) ride over and are lifted by the forwardly inclined surface 12 of the shuttle wood, they pass along the correspondingly curved surface 14 of the threading block apron without meeting any obstruction or projection tending to break the warp threads, and, similarly, as the warp threads pass from the surface 14 of the apron on to the shuttle wood adjacent the breast of the shuttle they ride upon the correspondingly curved surface formed in the wall of the shuttle wood, until, finally, when they pass on to the curved surface of the shuttle wood between the breast of the shuttle at 10 and the end of the curved portion of the shuttle body at 9, they are finally lifted sufficiently to permit the shuttle to pass through the shed without danger of breaking or ruptur-

ing any of the warp threads in the upper 65 plane of the shed.

It will be noted, as indicated in Figs. 1, 2 and 4, that the joint 15 between the curved surface of the front wall of the shuttle and the apron, is flush, or coincides with the 70 curve of the shuttle wood and apron, so that no projection is formed at this point calculated to catch or break the warp threads. Likewise, the forward edge 16 of the apron 75 which merges into the curve of the shuttle wood in front of the side delivery eye, presents no obstruction to the free passage of the warp threads as the shuttle passes through the shed.

As indicated in Figs. 3 and 4, the warp 80 threads are gradually lifted as the shuttle passes through the shed and, as indicated more particularly in the diagrammatic view, Fig. 4, the warp threads bear upon the leading or forward curved portion 12 of the 85 shuttle wood and pass on to the similarly curved portion of the apron 13, and from thence pass on to the similarly curved portion of the shuttle wood adjacent the breast 10 of the shuttle and to the beginning of the cut-away portion of the shuttle wood at 9, without at any time being subjected to an abrupt lift calculated to break the warp threads, or to any obstruction between the 90 shuttle wood and apron of the threading block.

As indicated in Fig. 1, the frontwardly, downwardly and forwardly inclined surface formed in the shuttle wood has its top portion below the back wall 17 of the shuttle body, so that as the shuttle enters the shed, the front wall thereof may gradually lift the warp threads in the upper plane of the 100 shed with an easy, gradual, rising motion, until, when the shuttle is fully in the shed, the warp threads pass from the end 9 of the cut-away portion on to the front wall of the shuttle back of such end 9, which is or may be of the same height as the back 105 wall of the shuttle.

The cutting away of the shuttle wood to form the gradual curvature described is liable to detract from the desired strength of the shuttle where the binder pressure is most effective as the shuttle is arrested in the shuttle box and to overcome any liability of the shuttle being crushed or broken under the binder pressure the threading block is formed of non-yielding material which effectively supports the wood of the shuttle and may be of the general character of the threading block shown and described in the patent to Edward S. Stimpson, No. 1,538,224, May 19, 1925. As indicated in Fig. 5, it will be noted that the side wall 18 of the threading block lies inside of the front wall of the shuttle, and being formed 115 of non-yielding material, such as cast iron.

it effectively supports the shuttle wood at this point and overcomes any tendency of the binder pressure to crush or break the shuttle even though the front wall thereof has been cut away or rounded as hereinbefore described.

What is claimed:

1. In an automatically threading shuttle for looms, the combination of the shuttle body provided with a side delivery eye and having its front wall adjacent the fell of the cloth during weaving cut away in a frontwardly, downwardly and forwardly uniformly curved surface from a point back 10 of the shuttle breast to a point forward of the side delivery eye, and a threading block the side walls of which are laterally unyielding to compensate for and support the weakened front wall of the shuttle to prevent 15 breakage of the shuttle wood under the binder pressure and having an apron provided with a frontwardly, downwardly and forwardly extending curved surface in the same plane as the curved surface of the 20 shuttle wall that the warp threads in the upper plane of the shed may ride over the coinciding curved surfaces of the shuttle wall and apron without encountering any 25 obstruction from either.
2. In an automatically threading shuttle for looms, the combination of the shuttle body provided with a side delivery eye and having its front wall adjacent the fell of the cloth during weaving cut away in a 30 frontwardly, downwardly and forwardly 35

uniformly curved surface to a point frontward of the side delivery eye and the top of which curved surface gradually decreases in height relative to the back wall of the shuttle, and a cast iron threading block 40 which supports the front wall of the shuttle against the binder pressure and having an apron with a similarly curved surface that the warp threads in the upper plane of the 45 shed may be gradually lifted by the coinciding curved surface without obstruction as the shuttle passes through the shed.

3. In an automatically threading shuttle for looms, the combination of the shuttle body provided with a side delivery eye and 50 having the wood of the front wall of the shuttle adjacent the fell of the cloth during weaving rounded into a frontwardly, downwardly, and forwardly extending direction from a point back of the shuttle breast to 55 a point forward of the side delivery eye to form a uniformly curved surface between these points devoid of projections that the warp threads in the upper plane of the shed may ride over such surface without being 60 broken when the shuttle is used in a narrow open shed, and a cast iron threading block having its unyielding wall underlying the wood of the shuttle breast to support the 65 same and prevent injury to the shuttle under the binder pressure.

In testimony whereof, I have signed my name to this specification.

HARRY A. DAVIS.
